US00D818457S

(12) **United States Design Patent** (10) **Patent No.:** **US D818,457 S**
(45) **Date of Patent:** **** May 22, 2018**

(54) **REMOTE**

- (71) Applicant: **Fitbit, Inc.**, San Francisco, CA (US)
- (72) Inventors: **Brian Dennis Paschke**, San Francisco, CA (US); **Mark Woolhiser Huang**, Burlingame, CA (US); **Gregoire Ludovic Vincent Vandenbussche**, San Francisco, CA (US); **Jonah Avram Becker**, San Francisco, CA (US); **Derek Jenchia Loh**, San Carlos, CA (US); **Bernhard Wildner**, San Francisco, CA (US)
- (73) Assignee: **Fitbit, Inc.**, San Francisco, CA (US)
- (**) Term: **15 Years**
- (21) Appl. No.: **29/579,653**
- (22) Filed: **Sep. 30, 2016**

(57) **CLAIM**

We claim the ornamental design for the remote, as shown and described.

DESCRIPTION

FIG. 1 is a front view of a remote of a headset. FIG. 2 is an isometric view of the remote of the headset of FIG. 1. FIG. 3 is an off-angle view of the remote of the headset of FIG. 1. FIG. 4 is a side view of the remote of the headset of FIG. 1. FIG. 5 is an opposite side view of the remote of the headset of FIG. 1. FIG. 6 is a back view of the remote of the headset of FIG. 1. FIG. 7 is a top view of the remote of the headset of FIG. 1; and, FIG. 8 is a bottom view of the remote of the headset of FIG. 1. The remote in the accompanying figures may be a part of a headset that may be placed, i.e., worn, in a person's ear. Stipple shading is used in the accompanying Figures to convey surface contouring and not texture. The broken lines shown in the drawings illustrate portions of the remote that form no part of the claimed design; additionally, dash-dot-dash boundaries indicate a transition from claimed subject matter to unclaimed environmental structure, as evidenced by the absence of shading within the boundary rectangle and the presence of shading outside of the boundary rectangle. For example, the "+" and "-" signs shown in the Figures as surrounded by dash-dot-dash boundaries are disclaimed using broken lines.
